UNITED STATES PATENT OFFICE.

HOWARD A. BAXTER, OF MELROSE HIGHLANDS, MASSACHUSETTS, ASSIGNOR TO PANAMA-PACIFIC INTERNATIONAL EXPOSITION CO., OF SAN FRANCISCO, CALIFORNIA, A CORPORATION OF CALIFORNIA.

DESIGN FOR A SPOON, FORK, OR SIMILAR ARTICLE.

46,556.

Specification for Design.

Patented Oct. 20, 1914.

Application filed July 20, 1914. Serial No. 852,124. Term of patent 3½ years.

To all whom it may concern:

Be it known that I, HOWARD A. BAXTER, a citizen of the United States, residing at Melrose Highlands, in the county of Middlesex and State of Massachusetts, have invented a new, original, and ornamental Design for a Spoon, Fork, or Similar Article, of which the following is a specification, reference being had to the accompanying drawings, forming part thereof.

Figure 1 is a front elevation of a spoon,

showing the application of the design. Fig. 2 is a rear elevation of the same. Fig. 3 is a cross section on line 3—3 of Fig. 1.

I claim:—

The ornamental design for spoon, fork or similar article, as shown.

HOWARD A. BAXTER.
